CLAIM

The ornamental design for a telephone attenuation block or similar article, substantially as shown and described.

DESCRIPTION

FIG. 1 is a front elevational view of a telephone attenuation block or similar article showing my new design;

FIG. 2 is a top plan view thereof;

FIG. 3 is a rear elevational view thereof;

FIG. 4 is a side elevational view thereof, the opposite side being a mirror image;

FIG. 5 is a vertical sectional view as seen from the plane 5—5 in FIG. 1; and

FIG. 6 is a bottom plan view thereof.

The slots in FIG. 3 and the terminals shown in FIG. 6 are partially shown for illustrative purposes only.

FIG. 1.
